UNITED STATES PATENT OFFICE.

BENJAMIN S. FOREMAN, OF MORRISON, ILLINOIS.

IMPROVEMENT IN PRESERVING RAILROAD-TIES.

Specification forming part of Letters Patent No. 43,191, dated June 21, 1864.

To all whom it may concern:

Be it known that I, BENJAMIN S. FOREMAN, of the town of Morrison, in the county of Whiteside and State of Illinois, have invented a new and Improved Mode of Preventing Railroad-Ties from Rotting; and I do hereby declare that the following is a full and exact statement of the material used and description thereof, reference being had to the accompanying drawing, and to the letters of reference thereon.

The nature of my invention consists in providing a railroad-tie with an aperture at either end inside of the rail and put therein a composition of salt and corrosive sublimate, which prevents the tie from rotting, holds the spikes in said tie to their proper place, and hardens the wood in said tie.

To enable others to use my invention, I will describe the composition and the manner of applying it more fully. Take a railroad-tie, either laid in the track or otherwise, and at a point six inches inside of where the iron rests thereon bore a hole in the upper or face side,

two inches in diameter and five inches deep, as shown at A in the accompanying drawing. In this aperture I put a composition of the following ingredients and in the following proportions, viz: Three ounces of corrosive sublimate to one pound of common salt. After having filled the hole with this composition, I insert a plug of wood one inch in thickness, the grain of the wood in the plug to run parallel with the grain of the wood in the tie, and to be firmly driven in. This compound will prevent the tie from rotting and hold the spikes, as shown at B in Fig. 2, and hardens the timber.

What I claim as my invention, and desire to secure by Letters Patent, is—

The application to railroad ties of a composition made of the materials and applied as and for the purpose herein set forth and described.

B. S. FOREMAN.
